STATIONERY.

1,385,992.

Specification of Letters Patent.

Patented Aug. 2, 1921.

Application filed May 13, 1918. Serial No. 234,089.

To all whom it may concern:

Be it known that I, EDGAR A. Gove, a citizen of the United States, residing at New York, in the county of New York and State of New York, have invented new and useful Improvements in Stationery, of which the following is a specification.

This invention relates to stationery, pertaining more particularly to means for combining indicia of different characteristics in a single sheet structure for mailing purposes as an inclosure.

In commercial practice, and especially where it is desirable to provide inclosures which pertain to various subjects-matter, it is the general practice to carry the indicia relative to such individual subject-matter on sheets separate from those carrying other data or subjects-matter, the several sheets then being folded and inclosed within the envelop for mailing purposes. For instance, a printed bulletin, which may be more or less in the form of an advertising circular, accompanies a letter to an individual, both being inclosed. Or, a statement of account, instead of carrying a personal notation thereon, may be accompanied by an individual letter. In either case, there is not only a requirement of care in assembling the various inclosures, but, in addition, there is a requirement of providing separate supplies, separate printing operations, etc. Furthermore, there is no assurance that the inclosure to the personal communication is of the desired or intended type.

One of the factors which tend to more or less necessitate operations of this type are the limitations which are provided by the use of the typewriter, and the more or less prevalent method of obtaining copies of letters by the use of carbon sheets, the standard typewriter being arranged to receive paper of limited width.

The present invention is designed to provide a more efficient solution of the problems which are necessarily inherent to the methods above indicated, by the use of a single sheet structure, and so arranging the indicia thereon as to permit folding along lines which will serve to naturally distinguish the indicia in accordance with its characteristics, the folding of the sheet on these lines making it of a size adapted to be readily received within a typewriting machine and at the same time permit of obtaining a carbon

copy of the personal communication, or permit, if desired, a letter press copy thereof to be made, without affecting the unitary sheet structure. As a result, assurance is not only had that the proper indicia supplemental to the personal communication accompanies the latter without liability of error of inclosure or its omission, but in addition, so presents the different indicia as will enable the recipient to readily separate the different indicia without mutilating or destroying the integrity of either of the characteristic indicia. In addition, it permits of combining indicia or data pertaining to a class or the public generally—as for instance in the form of a bulletin—and personal indicia in the form of a communication pertaining to special subject-matter. For instance, the bulletin may be in the form of a catalogue or price-list and the letter communication pertain to one or more of the items of the list, in which case the sheet may be folded in such manner as to expose the particular portion of the bulletin list concurrently with the exposed letter contents, the position of the letter section of the sheet being such as to permit folding for this purpose.

To these and other ends, the nature of which will be readily understood as the invention is hereinafter disclosed, said invention consists in the improved construction and combination of parts hereinafter more fully described, illustrated in the accompanying drawings, and more particularly pointed out in the appended claims.

In the accompanying drawings, in which similar reference characters indicate similar parts in each of the views:

Figures 1 and 2 represent the opposite faces of a three-section sheet which may be employed in carrying out the general principles of the present invention.

Fig. 3 is a view of the sheet of Figs. 1 and 2 folded.

Fig. 4 is a view similar to Fig. 3 in which but two sections are employed.

The invention is capable of use in many forms a few of which are more particularly described herein, but it is to be understood that the specific forms disclosed are more or less illustrative and are intended mainly to indicate the general character of the invention.

In each of the forms, however, there are a

few characteristic features which are common in all of the forms and upon which the invention is based. Among these are the following:—

- 5 (a) the sheet is of rectangular contour and such as can be readily printed upon on one or both faces; (b) the sheet is foldable into two or more sections; (c) each section has its head in the same relative position and 10 so arranged that the general direction of indicia feeding is the same as the general direction of the folding lines, a form which is somewhat similar to the form of a folder; (d) one end section has one or both of its 15 faces formed to permit typing or writing of the personal communication, and (e) this latter section is preferably, although not essentially, of a width less than the corresponding width of the remaining section or sections, so that the folded sheet places the letter section in superposed relation to another section which carries indicia of a generally different type. Where the sections are of 20 different width a portion of the underlying section will be exposed concurrently with the section carrying the personal communication. This general arrangement permits the section carrying the personal communication to be torn from the remainder of the sheet, if desired, without disturbing the indicia of either 25 the personal communication section or the remaining section or sections, thus enabling the entire sheet structure to be filed as a unit, to be separated into its parts and filed separately, or to be separated and the non-personal portion entirely discarded. In either 30 case, however, the attention of the recipient of the personal communication is inevitably called to the contents of the remainder of 35 the sheet—whether such remainder is referred to directly within the personal communication or not.

In Figs. 1 and 2 I have shown, more or less diagrammatically, two sides of a sheet 40 adapted to carry out one form of the present invention, this sheet being rectangular in form and normally folded on the lines 10 and 11, thus dividing the sheet into three sections—*a*, *b* and *c*. As shown, the folding 45 lines are so arranged as to provide sections *b* and *c* of substantially equal area, while section *a* is of considerably less area, all of the sections, however, being substantially equal in length in one dimension, this length 50 corresponding to the direction of length of the folding lines 10 and 11, the difference in area being provided by the decrease in dimension of section *a* in a direction transverse to the folding line. In this form, section *a* forms the section for the personal 55 communication, and may have either or both faces formed to receive the contents of such personal communication, and this may include the business heading which is usually 60 located at the head of a letter sheet.

Sections *b* and *c* as shown in Figs. 1 and 2, are in the form of a printed bulletin, producing the effect of a four-page leaflet of comparatively large size, the contents of the leaflet being printed matter and applicable 70 either to the public in general or to a particular class of the public. For instance, if the commercial house which is utilizing the invention, is of a type devoted to a particular business—as for instance jewelry—75 the contents of sections *b* and *c* preferably relate to news items or information pertaining to jewelry, the contents thus becoming more or less a bulletin of useful information 80 pertaining to the particular type of business and which may tend to interest the individual recipient of the personal communication, although the printed matter is of general information suitable for general distribution. As will be understood, the fact 85 that sections *b* and *c* are integrally connected with section *a*, gives assurance to the writer of the personal communication that the general information contained in the bulletin service connected thereto must 90 accompany the personal communication into the hands of the recipient of the communication, and the difference in width of section *a* as compared to either of the sections which they overlie, insures that in reading 95 the communication a portion at least of the printed bulletin is exposed, thus calling the attention of the recipient to the contents of the bulletin.

As will be seen, the head of each of the 100 sections is at the same end of the section, thus providing that in reading each section, the general direction of reading is the same, the lines of folding extending in the same general direction. And since section *a* is an 105 end section—either at the right or the left as may be desired—it is foldable to provide the topmost section of the folded sections and thus be in suitable position for typing the personal communication, it being readily 110 understood that a carbon sheet and the copy sheet can be readily inserted between section *a* and the underlying section to provide for obtaining a carbon copy of the communication if desired, it being obvious that the 115 sheet may be inserted into the typewriter in its normally-folded condition, so that the limits as to width of sections *b* and *c* is limited only by the width of sheet possible to be introduced into the typewriting machine. 120

Obviously, section *a* may be folded in either direction and thus be folded on to either face of section *b* or, on to the outer face of section *c*. This is of advantage in connection with certain uses, as for instance, 125 where it is desired to use sections *b* and *c* for the purpose of carrying special matter to which particular attention is to be called in the personal communication, in which case the particular column of sections *b* and *c* 130

which is exposed concurrently with the personal communication as section *a* overlies the particular face of the remaining sections would carry the data which forms the basis for such information. Where this data may be located on each of the three faces referred to, it is preferred to arrange the opposite faces of section *a* as capable of receiving the personal communication, that 10 face of section *a* which would be exposed concurrently with the desired column when the section is folded on to the face carrying the column, being employed as the face which carries the communication. However, where sections *b* and *c* carry general 15 bulletin information, and there is no particular necessity for emphasizing a particular part of the bulletin, one of the faces of section *a* may be utilized for the personal communication, the other face carrying advertising or general matter and may, if desired, carry a coupon, as for instance indicated in 20 Fig. 1. In such general use, section *a* may be folded on top of section *c* and thus place 25 the communication as the outer face of the sheet, or section *a* may be folded to extend between folded sections *b* and *c*, thus more or less hiding the communication. Or, the 30 communication may be placed on that face of section *a* which forms the under face of the section when the latter is folded, the recipient, in such case, simply unfolding section *a* to gain access to the personal communication.

35 From the above it will be readily seen that the commercial heading or headings of section *a* may be provided concurrently with the printing of sections *b* and *c*, so that the entire sheet requires no separate handling.

40 for the purpose of printing, and the additional size of the paper required by forming the three sections as an integral whole does not add materially to the expense of the paper; in fact, the paper cost will be generally decreased through the use of non-special paper which is made possible through the fact that the folded sheet is of ply formation.

45 In Fig. 4 I have shown the invention as applied to a two-section sheet, section *c* being omitted, section *b* carrying the bulletin material, section *a* providing for the personal communication of information as in the three-section form, section *a* being folded to overlie the desired face of section *b*.

50 With either the two-section or three-section sheet, section *a* may be bodily removed on line 10—which may, if desired, be of a weakened line formation—enabling the personal communication to be filed as such and the remaining section or sections filed away or destroyed as the recipient may desire, it having been brought to the attention of the recipient by reason of its connection with 55 section *a*.

While the invention is designed more particularly for use in relations such as above indicated, it is not limited to such use, being adapted for other uses, such for instance as in cases where it is desirable to provide 70 a personal communication in connection with a statement of account and where it may not be desirable to place the communication directly upon the statement. In such use, the statement of account would be 75 carried, for instance, by section *b*, section *a* carrying the personal communication, and since the two sections are capable of being separated without destroying the general characteristics of either, the two sections 80 which would be employed can be separated and filed in their individual records. Obviously, in this use, either or both faces of section *a* may be utilized for the personal communication, or one face may be utilized 85 for advertising or other purposes as may be found desirable.

As will be understood, the invention provides for combining in one sheet indicia having different general characteristics. For instance, the indicia of one general characteristic may be that designed for a general class and adapted for general distribution, while the indicia of different characteristic is that which is involved in the personal communication; or, the monthly statement and personal communication sections would provide 90 for indicia of different characteristics. In each case, however, the indicia of personal communication is maintained separate from 95 the remaining indicia and capable of separation therefrom, leaving the indicia of either characteristic unimpaired when separation is had.

While I prefer to locate the folding lines 100 so as to provide section *a* of less width than the adjacent section, this may be varied to meet individual use and desire, and such variation from this formation may extend to a point where sections *a* and *b* are of equal dimensions.

105 As will be understood, the invention is of wide application and the particular form in which it may be employed may vary in accordance with the particular use to which it is to be applied.

110 And I desire to be understood as reserving the right to make any and all such changes or modifications that may be found necessary in meeting these conditions, in so far as the same may fall within the spirit and scope of the invention as expressed in the accompanying claims.

115 What I claim is:

1. A combined letter head and form, comprising a first leaf having letter head indicia thereon and having a blank space for the insertion of a message, and a second leaf having permanent indicia thereon connected to one side edge of the first leaf throughout 120

125

130

- its length, said first leaf being arranged to fold along said edge into juxtaposition with said second leaf and being of less width than said second leaf, whereby when so folded a portion of the permanent indicia on said second leaf is exposed, the two leaves being formed by the folding of a single integral sheet.
2. A combined form and blank comprising a first leaf having a blank space for the insertion of a message and a second leaf of the same height as the first leaf throughout, connected to a side edge thereof and arranged to fold along said edge into juxtaposition with said first leaf, the second leaf having permanent indicia inscribed thereon, and a third leaf connected to the other side edge of the second leaf and arranged to fold along said edge into juxtaposition with said second leaf, the third leaf also having permanent, 20 indicia inscribed thereon, said first leaf being of less width than the second leaf, with blank vertical spaces between the several adjacent leaves to provide space for folding, the connection between the first and second leaves being weakened to facilitate the ready separation thereof, said several leaves being formed by the folding of a single integral sheet.
- In testimony whereof I have hereunto set 30 my hand.

EDGAR A. GOVE.
